UNITED STATES PATENT OFFICE.

JEREMIAH R. KNAPP AND FRANK J. BOWEN, OF NORWALK, OHIO.

DESIGN FOR A MEAT-HOOK.

SPECIFICATION forming part of Design No. 32,320, dated March 6, 1900.

Application filed February 2, 1900. Serial No. 3,749. Term of patent 7 years.

To all whom it may concern:

Be it known that we, JEREMIAH R. KNAPP and FRANK J. BOWEN, citizens of the United States, residing at Norwalk, in the county of Huron and State of Ohio, have invented and produced a new and original Design for Meat-Hooks; and we do declare the following to be a full, clear, and exact description of the invention, such as will enable others skilled in the art to which it appertains to make and use the same, reference being had to the accompanying drawings, and to the letters of reference marked thereon, which form a part of this specification.

Our invention relates to designs for meat-hooks; and the essential feature of our design consists in a frame or body having its outer hooked end turned at an angle to the frame and which frame is at its opposite end first bent vertically, then upwardly and outwardly at a right angle, then turned horizontally forward in a line with the frame, and having its extreme end turned downward at an angle to the adjoining horizontal portion, as will be more fully described hereinafter.

In the accompanying drawings, which illustrate our design, Figure 1 is a perspective of the meat-hook complete. Fig. 2 is a side elevation of the same. Fig. 3 is a front end view.

A represents the body of the hook, and B the hook formed upon its outer end, and which

hook extends at right angles to the length of the frame. This frame B is curved or bent upwardly at C, and the horizontal portion D extends in a line with the horizontal portion F, but at a higher plane. At the rear end of the horizontal portion D the frame is turned vertically downward at right angles to the part G, and then this part G of the frame is curved upwardly and outwardly away from the part D any desired distance. The part H of the frame extends horizontally forward at right angles to the part G and in a line with the part D, and the rear end I of the frame is turned downward at right angles to the part H, as shown. By thus bending the rear end of the frame it is provided at its rear end with the two recesses or cavities J. The bent portion G of the frame, as shown in Fig. 3, is about the same width as the hook B, and this hook B and the bent portion G of the frame extend in a line with each other, as shown.

Having thus described our invention, we claim—

The design for a meat-hook substantially as shown and described.

In testimony whereof we affix our signatures in presence of two witnesses,

JEREMIAH R. KNAPP.

FRANK J. BOWEN.

Witnesses:

GEO. BARGEN,

S. T. A. VAN SCIVER.
